UNITED STATES PATENT OFFICE.

ROBERT H. LEVIS, OF ALTON, ILLINOIS.

DESIGN FOR A BOTTLE.

SPECIFICATION forming part of Design No. 27,906, dated November 30, 1897.

Application filed September 20, 1897. Serial No. 652,383. Term of patent 7 years.

To all whom it may concern:

Be it known that I, ROBERT H. LEVIS, a citizen of the United States, residing at Alton, in the county of Madison and State of Illinois, have invented a certain new and original Design for a Bottle, of which the following is a full, clear, and exact description, reference being had to the accompanying drawings, forming a part of this specification.

10 My invention consists in a design for a bottle comprising a central plain body portion surmounting and surmounted by ribbed portions extending longitudinally of the bottle and having intervening depressions.

15 Figure I is a view of the bottle in elevation. Fig. II is a transverse sectional view taken on the line II II, Fig. I.

1 designates the central portion of the body of the bottle of cylindrical form, which, with 20 the exception of any letters or characters it may be desired to form in or upon it, is plain or smooth.

At the base of the bottle are a series of ribs 2, while the spaces intervening between the ribs are in the form of depressions 3.

25 The upper end of the bottle-body is curved inwardly to the neck 4.

5 are ribs, and 6 depressions similar to those indicated by 2 and 3, said ribs and depressions extending from the smooth or plain portion 1 of the bottle-body onto the neck 4, but ceasing short of the mouth of the neck and leaving a plain or smooth portion 7 extending to the mouth of the bottle-neck.

30 35 I claim as my invention—

The design for a bottle, substantially as herein shown and described.

ROBERT H. LEVIS.

In presence of—

E. S. KNIGHT,
STANLEY STONER.
